UNITED STATES PATENT OFFICE.

JAMES FRASER, OF HILLCREST, EDGEMOOR, DELAWARE, ASSIGNOR TO THE SPEAK-MAN COMPANY, OF WILMINGTON, DELAWARE, A CORPORATION OF DELAWARE.

DESIGN FOR A COMBINATION FAUCET AND SOAP DISH.

Application filed March 5, 1928. Serial No. 25,678. Term of patent 7 years.

To all whom it may concern:

Be it known that I, JAMES FRASER, a citizen of the United States, residing at Hillcrest, Edgemoor, in the county of New Castle and State of Delaware, have invented a new, original, and ornamental Design for a Combination Faucet and Soap Dish, of which the following is a specification, reference being had to the accompanying drawing, forming part thereof.

The figure is a perspective view of a combination faucet and soap dish, showing my new design.

I claim:

The ornamental design for a combination faucet and soap dish, substantially as shown.

JAMES FRASER.
